F. L. CARSON
Inventor

Victor J. Evans

By attorney.

UNITED STATES PATENT OFFICE.

FRANCIS L. CARSON, OF BERKELEY, CALIFORNIA.

SURFACE-ROLLING DEVICE.

Application filed August 4, 1924. Serial No. 730,115.

To all whom it may concern:

Be it known that I, FRANCIS L. CARSON, a citizen of the United States, residing at Berkeley, in the county of Alameda and 5 State of California, have invented new and useful Improvements in Surface-Rolling Devices, of which the following is a specification.

This invention relates to improvements in 10 surface rolling devices and has particular reference to a machine for packing and compressing the earth preliminary to the covering of the same with a surfacing material, or for actually compressing the asphaltic material itself.

Objects of this invention are to provide 15 mechanical means whereby ditches of various widths may be properly rolled so as to compact the bottom and side walls thereof; 20 to produce a machine which may be accommodated to various widths and depths of ditches with a minimum amount of effort; and to provide a device which may travel along the ditch and be operated entirely 25 from one side thereof without the necessity of an anchor on the opposite side of the ditch.

A further object is to produce a machine 30 of this character which is simple in construction, easy to manipulate, strong, durable and highly efficient in use.

Other objects and advantages will be 35 apparent during the course of the following description.

In the accompanying drawings forming 40 a part of this specification and in which like numerals are employed to designate like parts throughout the same,

Figure 1 is a vertical cross section of a 45 ditch having my device positioned adjacent thereto,

Figure 2 is a fragmentary detail view of the boom attaching means,

Figure 3 is a fragmentary detail view 50 showing the construction of the telescoping boom,

Figure 4 is a top plan view of the roller construction,

Figure 5 is a cross section taken on the 55 line 5—5 of Fig. 4, and

Figure 6 is a top plan view of certain of the operating mechanisms.

In the accompanying drawings wherein 60 for the purpose of illustration is shown a preferred embodiment of my invention, the

numeral 5 designates the bottom of a ditch and the numerals 6 and 7 the side walls thereof, while the numeral 8 represents the ground level upon which my device travels.

At 9, I have shown a platform preferably 60 mounted upon movable tracks 11 and 12, which tracks are of the customary construction and operate through the medium of an engine 13, which drives a shaft 14 and has a bevel gear 16 mounted thereon. This bevel gear meshes with spur gears 17 and 18 65 freely rotatable upon a cross shaft 19, which shaft is journaled at 21 and 22 to the platform 9.

It will be noted that this shaft 19 has 70 slidably keyed thereto clutches 23 and 24 which are connected by a yoke 26, which yoke is movable through the medium of a lever 27. These clutches are adapted to be alternately brought into engagement with the gears 17 and 18 for the purpose of transmitting forward or backward motion to the shaft 19, which motion is transmitted through chains 28 and 29 to the tracks 11 75 and 12.

The numeral 31 designates a gear keyed 80 to the shaft 14, which gear meshes with a second gear 32 secured to a shaft 33. This shaft is mounted in bearings 34 and 36 and carries at its opposite end a freely rotatable bevel gear 37. The shaft 33 has also keyed 85 thereto a sliding clutch 38, while a gear 39 meshing with the gear 37 is journaled as shown at 41. This gear 39 meshes with a gear 42 keyed to a shaft 40, which shaft 90 carries a gear 46 keyed thereto and journaled as shown at 47 and 48. Mounted on this shaft 40 is a tubular sleeve 43 upon which is slidably keyed a gear 44. The sleeve 43 is reciprocated by a lever 50 which 95 causes the end of the sleeve to engage the gear 42, the gear and sleeve being formed so as to act as a clutch when brought together.

The gears 44 and 46 mesh with gears 49 100 and 51 mounted upon a shaft 52 upon which drums 53 and 54 are secured. These drums are provided with flanges which serve to limit the travel of the rope 56 during its winding and unwinding action.

It will be noted by viewing Figure 6 105 that one end of the rope 56 is wound about the drum 54 from the top, while the opposite end of the rope is wound about the drum 53 from the bottom. This rope ex- 110

tends over a pulley 57 carried upon the end of a telescoping boom 58 pivoted at 59 to the platform 9.

5 A pin 60 is placed in suitable perforations in the boom 58 to prevent the boom telescoping further than desired. This pin permits the adjustment of the amount of expansion of the boom to suit the requirements of the work.

10 This boom 58 is supported by a mast 61 through the medium of cables 62. It is of course understood that the mast 61 has conventional guy ropes as well as the boom 58, which guy ropes prevent undesired side motion. By adjusting the boom guys it is possible to swing the boom around the machine as shown in dotted lines in Figure 6.

15 The rope 56 has secured thereto rollers 63 and 64 which are mounted between a plurality of frames designated at 66, 67, 68 and 69. The frames 66 and 69 are pivoted to the axles of the rollers and are secured to the rope 56, as before mentioned, while the frames 67 and 68 are pivoted to the axles of the rollers and to each other thus making a flexible connection between the rollers and the rope.

20 The usual fire pan 71 is mounted within the rollers. In Figure 3 I have shown the telescoping action of the boom. This telescoping action is well known and needs no further comment.

25 The operation of my device is as follows:—

30 Assuming that the parts are arranged, as shown in Figures 1 and 6, the tracks 11 and 12 are caused to propel the device as a whole to a suitable point adjacent the ditch, after which the rollers 63 and 64 are moved over the surface of the ditch as shown in Figure 1 by causing the rope 56 to be first operated in one direction and then in the opposite direction. This action is 35 accomplished through the medium of the motor 13 transmitting power to the drums 53 and 54 through the gears 31 and 32, shaft 33, gears 37, 39 and 42 thence to sleeve 43 and shaft 40 and by gears 44 and 46 to gears 49 and 51, thence by shaft 52 to the drums 53 and 54. The direction of travel of these drums is controlled by the clutch 38 in the well known manner.

40 It is therefore obvious that the rope will be unwound from one drum and around the other drum thus pulling the roller first

in one direction and then in the opposite direction by merely throwing the clutch 38 first into engagement with the gear 37 and then into engagement with the gear 42. 60 After a section has been rolled the device as a whole will be moved along the ditch and a new section rolled.

65 By releasing the sleeve 43 from its engagement with the gear 42 any slack in the rope may be taken up or extra rope may be let out to allow for the lengthening of the boom.

70 It is to be understood that the form of my invention herewith shown and described is to be taken as a preferred example of the same, and that various changes in the shape, size and arrangement of parts may be resorted to without departing from the spirit of the invention 75 or the scope of the subjoined claims.

Having thus described my invention, I claim:—

1. In a device of the character described, a movable platform, means for supporting said platform, a boom carried by said platform, a rope reaved over a pulley secured to the free end of said boom, a plurality of rollers attached to said rope, and means mounted on said platform for moving said rollers over the surface of a ditch by alternately reciprocating said rope. 80

2. In a device of the character described; a platform, means for movably supporting said platform adjacent a ditch, a telescopic boom pivoted to said platform, a mast secured to said platform and adapted to support said boom in a substantially horizontal position, a pulley secured to the free end of said boom, a rope reaved over said pulley, a plurality of rollers capable of being moved by said rope, a plurality of frames secured to said rollers and to said rope, means mounted on said platform for reciprocating said rope for the purpose of causing said rollers to be moved back and forth over the surface of said ditch. 95

3. A surface rolling machine comprising a vehicle, a boom carried thereby, a compressing element connected to said boom and vehicle, means operative from the vehicle for actuating the compressing element, and a source of power embodied in the vehicle for actuating the said means. 100

105 In testimony whereof I affix my signature.

FRANCIS L. CARSON.
